UNITED STATES PATENT OFFICE.

ISAAC L. GOFF, OF PROVIDENCE, RHODE ISLAND.

DESIGN FOR A BUTTON.

SPECIFICATION forming part of Design No. 18,628, dated September 25, 1888.

Application filed March 22, 1888. Serial No. 263,182. Term of patent 7 years.

To all whom it may concern:

Be it known that I, ISAAC L. GOFF, a citizen of the United States, residing at Providence, in the county of Providence and State of Rhode Island, have invented and produced a new and original Design for Buttons, of which the following is a specification, reference being had to the accompanying drawings, forming part thereof.

10 Figure 1 is a view of the face or upper surface of my newly-designed button. Fig. 2 is a side view of the same.

15 The leading feature of my design consists in a circular marginal line, the surface inclosed by which is divided into three equal and disconnected spaces by radial lines.

In the drawings, *a* is the face of the button, *b* the shank, and *c* the shoe. *d* is the circular marginal line. *e e e* are three lines radiating

from the center and extending to the marginal line *d*, so as to divide the circular field into three equal divisions, 1 2 3. The circular line and three radial lines present a plain smooth appearance and bring into prominence and clearly show the spaces 1, 2, and 3. 20

Having thus described my new and original design, I claim as new and desire to secure by Letters Patent—

The design for a button herein shown and described, the same consisting of the face thereof having the double annular lines and the double radial lines, which latter divide the surface of the button into three disconnected spaces, 1, 2, and 3, substantially as set forth. 30

ISAAC L. GOFF.
